UNITED STATES PATENT OFFICE

2,019,348

ELECTRIC CIRCUIT INTERRUPTER

Leland S. Hobson, Yeadon, Pa., assignor to General Electric Company, a corporation of New York

Application September 7, 1934, Serial No. 743,109

6 Claims. (Cl. 200—150)

My invention relates to electric circuit interrupters of the fluid-blast type and has for its principal object the provision of an improved circuit interrupter of the aforesaid type particularly adapted to the use of an arc-extinguishing liquid, as water, which is partially conducting as contrasted with the usual circuit breaker oil.

The use of a readily vaporizable and non-inflammable arc-extinguishing liquid, as water, in electric circuit interrupters has a number of advantages including practically instantaneous generation of adequate blast pressure upon opening of the circuit, elimination of fire hazard and decreased cost. In accordance with my invention, an electric circuit interrupter is provided with an explosion pot containing an arc-extinguishing liquid of the character above referred to, and the explosion pot which forms a part of the movable contact structure is positioned above the level of a separate body of similar arc-extinguishing liquid in the closed circuit position and arranged to be lowered into said liquid for refilling by and in accordance with the circuit opening operation.

My invention will be more fully set forth in the following description referring to the accompanying drawing, and the features of novelty which characterize my invention will be pointed out with particularity in the claims annexed to and forming a part of this specification.

Referring to the drawing, the single figure thereof is an elevational view, partly in section, of an electric circuit interrupter of the fluid-blast type embodying my invention.

The circuit interrupter illustrated comprises a main tank or casing 1 containing a suitable arc-extinguishing liquid 2, as water. Relatively movable contact structure for interrupting the circuit is disposed within the tank and in the closed circuit position shown is disposed in the gas or air space above the level of the liquid 2. The aforesaid contact structure comprises a pair of fixed contacts 3 mounted at the lower ends of the conventional lead-in bushings 4 and a conducting bridging member 5 arranged to engage and interconnect the fixed contacts 3 in the closed circuit position.

The movable contact structure, in addition to the bridging member 5, comprises an explosion pot 6 of insulating material formed in the present instance as a cylinder or tube closed at its opposite ends and enclosing the bridging member 5. The explosion pot 6 is provided at its upper side with apertures 7 for receiving the fixed contacts 3 and for serving as the usual blast openings during circuit interruption.

The explosion pot 6 when in the closed circuit position shown likewise contains an arc-extinguishing liquid 2' similar to that in the tank so that upon lowering of the movable contact structure, as by the usual operating or lift rod 8, the arcs formed on separation of the contacts 3 and 5 instantly vaporize a portion of the liquid and generate high pressure within the explosion pot. As the contacts 3 pass through the exhaust openings 7 the pressure within the explosion pot is effective to direct arc-extinguishing blasts of steam and of liquid through the arcs, causing interruption of the same.

In operation, the circuit is opened by lowering of the movable contact structure into the liquid 2 at the lower part of the main tank. Arcing is interrupted by the explosion chamber effect above described. After a single circuit interrupting operation, particularly in case of currents of larger magnitude, an appreciable part of the arc-extinguishing liquid within the explosion pot 6 has been ejected in the form of vapor and atomized liquid. By immersing the explosion pot 6 within the liquid 2 at the end of each circuit opening operation, the explosion pot is automatically refilled so as to be in readiness for another circuit interrupting operation immediately after reclosure.

For the purpose of limiting the arcing pressure within the explosion pot, as during the interruption of short circuit currents, pressure relief means may be provided. In the arrangement shown the opposite ends of the explosion pot 6 are normally closed by valves 9 biased into seating engagement with the ends of the insulating cylinder by springs 10. Each spring 10 is mounted on a valve guide rod 11 secured at one end, as at 12, to the bridging member 6 and having at its free end an adjusting nut 13 for determining the opening pressure of the valve.

The operating means for the movable contact structure likewise includes an insulating barrier 14 which is formed as a plate of insulation suitably secured to the movable contact structure intermediate the fixed contacts 3. The insulating barrier 14 is effective to prevent arcing or flash-over between the stationary contacts 3 when the circuit breaker is in open position, the stationary contacts 3 in such position being isolated in air.

In cases where infrequent operation of the circuit breaker is required, evaporation of the arc-extinguishing liquid may be substantially prevented by a very small amount of oil on the 55

liquid 2. After each refilling operation a light oil film will of course be present on the liquid in the explosion pot 6, thereby preventing evaporation. Likewise when the circuit interrupter is 5 intended for outdoor use a suitable anti-freeze, as ethylene glycol, may be used where water is the arc-extinguishing liquid.

A practical advantage of the above described arrangement is that the "down-break", i. e., 10 downward movement of the bridging contact during circuit interruption, is generally preferable to the upward movement previously used in circuit breakers using a conducting liquid. The down-break has the aid of gravity to accelerate the 15 moving contact.

Furthermore, throwing off of water or steam, which might be expected in the prior up-break types of circuit breakers using water, is here 20 prevented by the main tank and its insulating lining which completely enclose the interrupting element.

It will be apparent that individual or separate explosion pots for each pole of the breaker may 25 be used instead of the tubular explosion pot common to both poles, illustrated by way of example.

It should be understood that my invention is not limited to specific details of construction and arrangement thereof herein illustrated, and that changes and modifications may occur to one 30 skilled in the art without departing from the spirit of my invention.

What I claim as new and desire to secure by Letters Patent of the United States is:

1. An electric circuit interrupter of the fluid-blast type comprising relatively movable contact structure including a movable explosion pot containing an arc-extinguishing liquid, the arc formed upon separation of said contact structure causing an arc-extinguishing blast from said pot, 35 and means for refilling said explosion pot with similar liquid by and in accordance with the circuit controlling operation, said contact structure arranged so that the same is spaced by air in the open circuit position.

2. An electric circuit interrupter of the fluid-blast type comprising relatively movable contact structure including a movable explosion pot containing an arc-extinguishing liquid, a tank in 40 which said contact structure is mounted likewise containing similar liquid, said contact structure in the closed circuit position being positioned above the liquid level in said tank, and means for refilling said explosion pot with liquid from said tank by and in accordance with the circuit controlling operation.

3. An electric circuit interrupter of the fluid-blast type comprising a tank containing an arc-extinguishing liquid, relatively movable contact structure for coacting above the level of said liquid including an explosion pot likewise containing arc-extinguishing liquid, and means for lowering said explosion pot in said tank for opening the circuit, said explosion pot being refilled with liquid from said tank by and in accordance with said circuit controlling operation. 5

4. An electric circuit interrupter of the fluid-blast type comprising a tank containing an arc-extinguishing liquid, a pair of fixed contacts mounted in said tank, coacting movable contact structure including a conducting bridging member, a tubular insulating explosion pot movable with said bridging member, said explosion pot having openings for receiving said fixed contacts and normally containing arc-extinguishing liquid, the aforesaid contact structure disposed above 20 the level of the liquid in said tank in the closed circuit position, and means for lowering said bridging member and explosion pot for effecting the circuit opening operation, said explosion pot being immersed in the liquid in said tank in 25 the open circuit position.

5. An electric circuit interrupter of the fluid-blast type comprising a tank containing an arc-extinguishing liquid, a pair of fixed contacts mounted in said tank, coacting movable contact structure including a conducting bridging member, a tubular explosion pot composed of insulation enclosing said bridging member, and pressure relief valves at opposite ends of said explosion pot, said explosion pot normally filled with 35 a similar arc-extinguishing liquid and positioned together with said fixed contacts above the level of the liquid in said tank in the closed circuit position, and operating means including an insulating barrier connected to said explosion pot between said fixed contacts for lowering said explosion pot and effecting a circuit opening operation, said explosion pot being immersed in the liquid in said tank so that it is refilled with liquid 40 prior to the circuit closing operation. 45

6. An electric circuit interrupter comprising a tank containing a conducting arc-extinguishing liquid, fixed contact structure mounted above the level of said liquid, coacting movable contact structure including an explosion pot containing 50 a similar liquid, and means for lowering said movable contact structure into the liquid in said tank thereby effecting the circuit opening operation.
